UNITED STATES PATENT OFFICE.

DAVID RANKEN SHIRREFF GALBRAITH, OF AUCKLAND, NEW ZEALAND,
ASSIGNOR OF ONE-HALF TO WILLIAM STEUART, OF AUCKLAND,
NEW ZEALAND.

ELECTRIC FURNACE.

SPECIFICATION forming part of Letters Patent No. 779,844, dated January 10, 1905.

Application filed October 27, 1903. Serial No. 178,787.

To all whom it may concern:

Be it known that I, DAVID RANKEN SHIRREFF GALBRAITH, analytical and consulting chemist, Fellow of the Institute of Chemistry of Great Britain and Ireland, of The Ladies Mile, Auckland, New Zealand, have invented certain new and useful Supplementary Apparatus for the Reduction of Iron-Sand, Iron Oxids, and other Suitable Substances, of which the following is a specification.

This invention relates to an electrical furnace for the treatment of iron-sand and other refractory ores or metal-bearing substances, and has special reference to the treatment and of the arrangement of the fusing zone of the furnace, whereby the shower charge of the material under treatment while being deflected by interceptors crossing the fusing zone is repeatedly caused to complete and act as part 20 of the electric circuit and be raised to incandescence by reason of its resistance, in consequence whereof the utmost effect incidental to the electric current will be obtained and the treatment will be expedited.

In carrying out the invention the fusing zone of the furnace laterally stepped is fitted crosswise with a plurality of non-conducting interceptors arranged grid-like in superposed relation, and electric conductors are led at the 30 ends of the interceptors into the fusing zone, and the shower charge is fed centrally onto the interceptors, so that as the material under treatment falls on and lies along each one of the plurality of superposed interceptors and 35 on and along the electric conductors at its ends the material will electrically connect such conductors and complete the electric circuit and will incandesce by means of its resistance to the electric current.

On the accompanying drawings, Figure 1 represents the furnace and the receiver in sectional elevation. Fig. 2 is a sectional elevation at right angles to Fig. 1, and Fig. 3 is an enlarged sectional perspective view representing the fusing zone characteristic of this invention.

The apparatus represented in the drawings consists of a furnace *a*, composed of blocks *d*,

inclosed by casings *e e'*, and provided with a cap *r* having a feed-hole *s*, and a crucible *h*, 50 or receiver of the products of the furnace inclosed by casings *f f'*, serving as a base to the furnace and having a gas-inlet *g* with crossing incandescents *i*, and slag and metal outlets *p q*, the furnace and its casing being 55 recessed or chambered at *j* to accommodate the electric conductors *t* and terminals *t'*, and the furnace having the sides of its fusing zone repeatedly stepped at *m*, so as to form guide-chutes to deflect and direct the descending 60 iron-sand or other substances.

According to the present invention the material under treatment while traversing the fusing zone of the furnace showerwise in thin streams is caused to complete and act as part 65 of the electric circuit at the time of or while being deflected in its fall by each respective one of the plurality of interceptors, whereby in its fall it is caused to be repeatedly acted on by the electric current to the fullest advantage. To attain this end, non-conducting interceptors *c* are placed across the fusing zone in superposed relation and located in recesses *j* in the furnace sides, and carbon or other conductors *B* are adapted to rest on the ends 70 of and to be partly embedded in the interceptors and to project into the furnace fusing zone. V-shaped troughs *A*, having perforated bottoms, are also arranged across the furnace a short distance above and longitudinally central of the upper interceptors, so as to direct the material under treatment in thin shower-like streams directly thereonto.

The material to be treated after preliminary treatment is fed through the cap feed-hole into 85 the V-troughs, which direct it in streams centrally over the under non-conducting interceptors and their respective end conductors, in consequence whereof while the material rests on the interceptors and conductors it 90 electrically connects the latter and completes the electric circuit and by reason of its resistance is heated to incandescence, such action being repeated in descending succession as the material is intercepted and deflected by 95 the successively lower interceptors while the

ascending current of reducing-gas delivered from the receiver acts continuously on the material.

The intercepters are made of bauxite or 5 other suitable refractory material and may be made of any suitable form and arranged to be rotatable.

What I claim as my invention, and desire to secure by Letters Patent, is—

- 10 In an electric furnace for treating iron-sand and other refractory ores and substances comprising an incased furnace recessed to accommodate electric connections in circuit with a source of electric energy and having the sides 15 of its fusing zone stepped internally with inclined chutes, a plurality of non-conducting intercepters mounted within the furnace at the stepped fusing zone and arranged in super-

posed relation and adapted together with such stepped parts of the furnace to deflect the material under treatment successively to the next lower intercepters and with electric conductors leading into the fusing zone at the ends of each interceptor, and a plurality of V-shaped troughs perforated at their bottoms 25 and serving to direct the material in thin streams longitudinally central of the under series of intercepters and conductors, whereby, the shower charge of the material will be caused at the time of each of its interceptions 30 to complete and act as part of the electric circuit; as set forth.

DAVID RANKEN SHIRREFF GALBRAITH.
